DESIGN FOR AN EYESHIELD

Joseph E. Du Bois, Buffalo, N. Y., assignor to Virginia I. Du Bois, Rita C. Sterne, Eileen Silbert, Florence E. Taylor, all of Buffalo, N. Y., and Lauriene T. Holzworth, North Tonawanda, N. Y.

Application December 1, 1943, Serial No. 111,845

Term of patent 14 years

(Cl. D57—1)

To all whom it may concern:

Be it known that I, Joseph E. Du Bois, a citizen of the United States, residing at Buffalo, in the county of Erie and State of New York, have invented a new, original, and ornamental Design for an EYESHIELD, of which the following is a specification, reference being had to the accompanying drawing, forming a part thereof.

The headband has been shown fragmentarily in Figures 3 and 4 for convenience of illustration.

I claim:

The ornamental design for an eyeshield, substantially as shown and described.

JOSEPH E. DU BOIS.
